C. W. BUCKLER

FIREPLACE HEATER

Filed May 11, 1922

Attorney

UNITED STATES PATENT OFFICE.

CARL WELLINGTON BUCKLER, OF LEXINGTON, KENTUCKY.

FIREPLACE HEATER.

Application filed May 11, 1922. Serial No. 560,161.

To all whom it may concern:

Be it known that I, CARL W. BUCKLER, a citizen of the United States, residing at Lexington, in the county of Fayette and State 5 of Kentucky, have invented certain new and useful Improvements in Fireplace Heaters, of which the following is a specification.

The purpose of my invention is to provide a fireplace heater having high efficiency as 10 a heat conserving device, and which may be manufactured and installed at relatively small cost. The heater comprises a hollow metal body, preferably cast in one piece, and having a base which underlies the grate, 15 and a back piece having a forward wall which overlies the grate, whereby the air which circulates through the heater will be heated by the flames and hot gases passing upwardly from the grate in contact with 20 the back portion and by the heat radiated downwardly from the grate on to the base portion. The back piece is provided with an air inlet in its upper portion, through which external air may be admitted to the heater, 25 and the base is provided with an outlet opening near its forward edge through which the heated air may pass out of the heater into a suitable conduit and thence through a register into the room. The draft in the chimney causes fresh air to be drawn continuously 30 into the heater and thence through the register into the room in which the heater is located.

In the accompanying drawing, 35 Fig. 1 is a central vertical section through a heater made in accordance with my invention, showing the same arranged in a fireplace and connected to a register in a room; and,

40 Fig. 2 is a perspective view of the heater, with a grate support attached, the latter being partly broken away.

Referring to the drawing, *a* represents the heater, and *b* represents a grate support 45 which may be of any desired form and may be secured to the heater body or separately supported on its base. The heater comprises a hollow metal body, preferably cast in one piece, and consisting of a hollow base 1, relatively flat and of such length, width and contour as to fit snugly within the walls of the fireplace at the bottom of the latter. A hollow back piece 2 projects upwardly from the rear of the base piece and fits against the

rear wall 3 of the fireplace, this back piece being of the same length, from side to side, as the base piece and adapted to fit against the side walls of the fireplace. The rear wall 2^a of the back piece is flat and lies against the wall 3 of the fireplace, while the forward wall of 60 the back piece has a part 2^b which extends upward from the base piece and substantially parallel with the wall 2^a to a point slightly above the grate 4, and a part 2^c which inclines forwardly and upwardly 65 from the part 2^b and overhangs the grate and the base piece. The base piece has an air outlet 5 at its forward edge, preferably projecting downwardly, as shown, and the back piece has an air inlet 6 in its upper part, this 70 inlet, as shown, being in the form of a short tube which, when the heater is in position, projects through an opening in the rear wall of the fireplace to admit fresh air into the heater. The heater proper may be cast with 75 or without the grate support *b*. Any suitable form of grate supporting means therefor may be provided and the support may be secured to the heater body or may rest upon the base of the heater. Preferably, the hollow 80 back piece is provided with internal baffles 9, projecting from its front and rear walls, to cause the air to take a longer course through the heater in contact with the heated metal; but these baffles may be omitted, if 85 desired.

The device is installed by placing it in the fireplace, as shown, and connecting to the outlet 5 a pipe 7 which is carried beneath the floor to a register 8, which may be inserted 90 in the floor or arranged in the room at any convenient point remote from the heater.

In operation, the doors and windows being closed, the draft up the chimney will cause 95 air to be drawn through the heater and register into the room, and this heated air replaces the air passing up the chimney. It is to be noted that the air receives heat from the fuel in the firebox throughout its course through the heater, since the part of the heater above the grate is in direct contact with the flames and hot gases, and the part of the heater below the grate, including the base, receives heat which is radiated downward from the fuel in the grate. As the heater can be made in one casting, of simple form, the cost of manufacture is relatively small, and because of the large heating sur-

face to which the air is exposed in its passage through the heater, the later is very efficient.

What I claim is:

- 5 1. The combination with a room having a fireplace and a flue leading therefrom, of a heater fitting within the fireplace without closing the flue, said heater comprising a closed metal casing having a base constituting a hollow hearth, a hollow back-piece extending upwardly from the rear part of the base, the front wall of said back-piece overhanging the base, said base-piece having an opening communicating with the room and 15 said back-piece having an opening in its upper part communicating with the atmosphere exterior to the room.
- 10 2. A heater, adapted to fit into a fireplace, comprising a closed metal casing having a base, constituting a hollow hearth, and a hollow back-piece extending upwardly from 20

the rear part of the base, the front wall of said back-piece overhanging the base, said base having an opening in its forward part and said back-piece having an opening in 25 the upper part of its rear wall.

3. A heater, adapted to fit into a fireplace, comprising a closed metal casing having a base, constituting a hollow hearth, and a hollow back-piece extending upwardly from 30 the rear part of the base, the front wall of said back-piece extending vertically upward from the base and thence inclining forwardly to the top of the heater and overhanging the base, said base having an opening in its forward part and said back-piece having an opening in the upper part of its 35 rear wall.

In testimony whereof I affix my signature.

CARL WELLINGTON BUCKLER.
